MAGNETIC MOTOR

George C. Armstrong, Pittsburgh, Pa., assignor
to Westinghouse Electric & Manufacturing
Company, a corporation of Pennsylvania

Application November 21, 1935, Serial No. 50,866

10 Claims. (Cl. 172—126)

This invention relates to magnetic devices and includes an arrangement that may be called a magnetic ratchet.

It is an object of this invention to produce rotation from the interaction of certain magnetic parts including a vibrating armature.

It is a further object of this invention to rotate a screw by the interaction of the stationary part of a magnetic circuit and a vibrating armature.

10 It is a further object to equip the armature in such an arrangement with a thread engaging the screw.

It is another object of this invention to produce a relatively slow movement from the comparatively rapid movement of a vibrating armature without the intervention of gears.

It is a further object of this invention to produce vibratory movements by means of alternating current and to employ the flux from such 20 a current to also induce movements of a rotatable body.

It is another object of this invention to equip the rotatable body and the vibrating armature in the last-mentioned object of the invention with cooperating threads.

It is a further object of the invention to so mount a rotatable magnetic body within the field of a stationary pole that it can be magnetically drawn into engagement with a vibrating armature and to provide a bias tending to hold it away from said armature.

It is a further object of this invention when the rotatable body is a screw to provide said bias either by a spring or by an end thrust on the screw.

35 Other objects of the invention and details of the structure will appear from the following detailed description and the accompanying drawing, in which:

40 Figure 1 is a top plan view of the device;

Fig. 2 is a side elevational view thereof;

Fig. 3 is a view in perspective of certain details; and

Fig. 4 is a diagrammatic view illustrating how 45 the device may be employed to operate a relay.

The device includes a magnetic circuit having a stationary or base portion 1 with two arms 2 and 3 extending upwardly from the base portion in the position illustrated in Fig. 2. The magnetic circuit is of laminated iron and the laminations are covered by side pieces. The laminations in the arm 3 terminate in an arcuate pole shown in dotted lines in Fig. 2. This arm carries a coil 4 adapted to be supplied with alternating current.

The side pieces, enclosing the laminations on the arm 3, extend above it, as indicated at 6, and afford support for a pivot 7, upon which an armature 8 is mounted. At the top, the side pieces 6 carry a bracket 10 supporting a plate 12 which carries abutments 13 and 14 for the upper ends of two springs 15 and 16. The springs bear against the upper face of the armature on opposite sides of the pivot 7 and so maintain the armature in a position of equilibrium. 10

The member 2 of the magnetic circuit is equipped with side pieces having brackets 19 at their upper ends. Holes are provided in the brackets 19 for loosely mounting screw 18. The screw is thus supported above the pole which is 15 the upper end of the member 2, indicated by dotted line 9. The end of the armature 8 adjacent the screw 18 is equipped with ribs 20 (see Fig. 3) adapted to engage in the threads of the screw 18. The side pieces of member 2 also 20 each carry a bracket 11 integral therewith but disposed at right angles thereto, which support flat springs 17 bearing against screw 18.

In the operation of the device, when the coil 4 is energized with alternating current, the 25 armature 8 is set into oscillation at a frequency twice that of the alternating current. The attraction between the left-hand end of the armature and the pole 9 at the upper end of the member 2 is productive of this vibration. The springs 30 15 and 16 are alternately compressed by the movements of the armature, and the position of equilibrium when the current oscillations pass through zero is that illustrated in Fig. 2. Fig. 3 illustrates the position of the armature when the 35 magnet is completely deenergized. In the position illustrated in Fig. 3 the teeth 20 are completely out of engagement with the screw 18.

The screw 18 is subject to the pressure of the 40 springs 17 and the flux between the armature 8 and the member 2. It is also subject to friction with the armature 8 or the teeth 20 during certain parts of the oscillations of the armature.

The analysis of these forces and their action 45 upon the screw is difficult but the result is that the screw in the construction illustrated rotates clockwise, as seen in Fig. 2.

The following is an explanation of this action as completely as present knowledge permits. When the armature 8 is set into vibration by the 50 alternating current, after a few cycles it acquires a state of steady motion, that is, vibration and during such vibration it is in the position most remote from the member 2 at the time when the current in coil 4 is passing through a maxi- 55

num. The polarity of the part of the screw nearest the armature 8 at such time is opposite to that of the armature, and magnetic attraction between them insures that the armature moving counter-clockwise, on its pivot will drive the screw clockwise, as seen in Fig. 2, during the downward motion of the armature end. As the current decreases the flux in the air gap between the armature 9 and the member 2 also decreases.

10 When this flux has fallen to zero the magnetism in the screw 18 has not reached zero. About the time that the current passes through zero the armature will have reached a position approximately like that illustrated in Fig. 2, and its 15 pole strength will have become zero. The screw will continue to have a polarity opposite to that of the armature at the beginning of this motion. After the current begins in the opposite direction the flux in the gap between the armature 8 and 20 the member 2 will be reversed, but not until this current reaches a certain strength will it reverse the polarity in the screw. Until this occurs there is slipping between the teeth 20 and the threads of the screw 18, not only because 25 of the magnetic repulsion between them, but also because of the action of the springs 17 tending to separate them. The screw will move under the action of the springs 17, but not far enough 30 to completely disengage the threads of the screw from the teeth 20.

At about the time that the current passed through zero, the armature was in the act of reversing its motion so that it was going upward, as seen in Fig. 2, during the time that the 35 screw was of the same polarity as the armature. This upward movement does not cause reversal in the rotary movement of the screw, because of the slipping which occurs while the screw is of the same polarity as the armature. After the 40 magneto motive force in the new direction has acquired sufficient strength to reverse the polarity of the screw it is again attracted toward the teeth 20 and the movement of the armature upward has a rotary effect upon the screw moving 45 it in a counter-clockwise direction. As the current increases the armature moves upwardly under the influence of the energy stored in the springs, reaching its upper position at approximately the time that the current has again 50 reached its maximum.

During the next half cycle the action is repeated, the armature descending and driving the screw clockwise until the armature reaches its lowermost position. Then there is slipping between the armature and the screw as the armature begins its upward movement, and finally the screw is driven counter-clockwise while the armature approaches its uppermost position and the current its maximum in the original direction.

55 It will thus be seen that the screw is driven clockwise for a complete quarter cycle of the current, then there is slipping between the screw and the armature for a portion of a quarter cycle of the current, and the armature is driven counter-clockwise for the remainder of said quarter cycle. During the next half cycle of the current this is repeated, the armature being driven clockwise for a quarter cycle, then slipping for a portion of the next quarter cycle, and being driven counter-clockwise for the final part of the second half cycle. The result of the whole series of actions during the cycle is that the armature is driven clockwise more than it is driven counter-clockwise. The armature, there-

fore, has a progressive movement in the clockwise direction as seen in Fig. 2.

During all of this time the screw 18 is in engagement with the teeth 20 and above-noted progressive clockwise movement of the screw results in a progressive longitudinal movement thereof. This movement may be employed to control contacts 25 placed within the path of the screw or to do any other useful work.

In Fig. 4, I have illustrated the application of 10 this device to a time-delay relay. In Fig. 4, closing the push-button 26 will energize the magnet 27 of a circuit-closing and self-holding switch. This has the effect of energizing a motor 28 and the coil 4 of the relay mechanism. The 15 motor rotor initially includes a resistor 29 in circuit with it. After the coil 4 has been energized for a predetermined period, the contacts 25 are closed, which has the effect of energizing the magnet 30 which operates a switch to cut 20 out the resistor 29.

Upon operating the push button 31 to deenergize the magnet 27, the magnet 4 is likewise de-energized and the armature takes the position illustrated in Fig. 3 with the teeth 20 completely 25 out of engagement with the screw 18. The screw 18, therefore, returns under gravity as illustrated, or any other bias provided, to its original position, and the contacts 25 open leaving the parts in their 30 original position.

It will be obvious to those skilled in the art that many variations are possible within the spirit of this invention. I, therefore, desire that the foregoing description and the drawing be regarded as illustrative only, not as limiting the 35 claims beyond the limitations actually expressed therein.

I claim as my invention:

1. In a magnetic motor, a vibratory armature, a magnetic circuit energized with alternating 40 current for keeping said armature in vibration and a movably mounted magnetic body inter-linked with the flux traversing said magnetic circuit and said armature, and means biasing said body to a given position whereby said body differs 45 at times in polarity from said armature while at other times has a similar polarity whereby the motion of said body produced by the vibrations of said armature will be cumulative.

2. In a magnetic motor, a magnetic circuit 50 including a stationary part and an armature, a coil on said stationary part, biasing means holding said armature yieldingly away from said stationary part, whereby when said coil is energized by alternating current said armature will 55 vibrate, magnetic means cooperating with said vibrating armature and means for biasing said magnetic means away from said armature whereby said means differs at times in polarity from said armature while at other times has a similar 60 polarity and thus produces rotation of said means through the vibration of the armature.

3. In a magnetic motor, a magnetic circuit including an armature, and a stationary part, a biasing means yieldingly keeping the armature 65 at a distance from the stationary part and affording an air gap, means for energizing said magnetic circuit with alternating current to cause said armature to oscillate, a rotatable body mounted in said air gap in position to contact 70 with the end of said armature but said rotatable body including means normally biasing it away from said contact, whereby the coaction of said oscillating armature and the means normally biasing the rotatable body away from the arma- 75

ture cause a motion of said rotatable body during energization of said magnetic circuit which will be cumulative.

4. In a magnetic device, an armature, opposed springs maintaining said armature in equilibrium, a magnetic circuit adapted to be energized with periodic current cooperating with said armature and maintaining it in vibration when said magnetic device is energized, a threaded member in position to be energized by said armature and a thread carried by said armature cooperating with said threaded member.

5. An electric motor comprising a magnet core having an air gap therein and including a movable part adjacent said gap, means generating a varying flux in the core and gap, means cooperating with the movable core part to effect oscillating movement thereof in accordance with the varying flux, a rotatably mounted magnetic member interlinked with the flux traversing said core and said movable part and means for biasing said magnetic member so that said member principally follows the movable part for oscillatory movements in a given direction whereby said member is caused to move in a step-by-step manner in substantially a given direction by the movable part of the core.

6. A ratchet type electric motor comprising in combination, an oscillating magnetizable member, means for generating a variable flux therein, and a rotatable magnetizable rotor spring biased away from one end of the oscillating magnetizable member and peripherally engaged by the adjacent end face of the oscillating magnetizable member during the portion of the movement when attraction exists between said oscillating member and said rotatable member.

7. A ratchet type electric motor, comprising in combination, an oscillating magnetizable member traversed by an alternating magnetic flux, a bearing, a magnetizable rotor loosely rotatably supported by said bearing adjacent to a face of said oscillating magnetizable member and adapted to be magnetically attracted into frictional engagement with the face of said magnetizable member to be rotated thereby in a succession of short peripheral movements.

8. A magnetic device comprising a magnet cir-

cuit having an air gap therein and including a movable part adjacent said air gap, means adapted to generate a varying flux in the circuit and across said air gap, spring means cooperating with the movable part of the circuit adapted to effect oscillating movement thereof in accordance with the varying flux, a rotatably mounted magnetic rotor disposed in said air gap and attracted and engaged by said movable part of the magnet circuit during a portion of the travel thereof, and spring means for biasing said rotor away from said movable part of the magnet circuit to restrict the period of such engagement of said rotor and said movable core part.

9. A magnetic device comprising a magnet circuit having an air gap therein and including a movable part adjacent said air gap, means generating a varying flux in the circuit and across said gap, spring means cooperating with the movable part to effect oscillating movement thereof in accordance with the varying flux, a rotatably mounted magnetic rotor having a threaded portion disposed in said air gap and attracted and engaged at its threaded portion by said movable part during a portion of its travel, and spring means for biasing said rotor away from said movable core part to restrict the period of such engagement of said rotor and said movable core part.

10. In a magnetic motor, an armature of magnetic material adapted to vibrate, a stationary frame, or stator, of magnetic material, and a movably mounted magnetic body, said armature, stator frame and movably mounted body comprising a magnetic circuit, means adapted to energize said magnetic circuit by an alternating current whereby the armature is caused to vibrate, said movable body being disposed near an end of the armature and an end of the stator so that the movable body moves as a function of the vibratory movement of the armature, and means adapted to substantially eliminate the effect of said armature on the movable body for a given portion of each cycle of the armature oscillation whereby the movements of the movable body will be cumulative.

GEORGE C. ARMSTRONG.
